CLAIM

The ornamental designs for a novel fluid dispensing stand and insert, as shown and described.

DESCRIPTION

FIG. 1 is a perspective view of a fluid dispensing stand and insert as assembled;

FIG. 2 is a front elevation view, thereof;

FIG. 3 is a rear elevation view, thereof;

FIG. 4 is a left side elevation view, thereof;

FIG. 5 is a right side elevation view, thereof;

FIG. 6 is a top plan view, thereof;

FIG. 7 is a bottom plan view, thereof;

FIG. 8 is a perspective view of the insert of the fluid dispensing stand and insert of FIG. 1 with the drip tray for attachment to the housing included in the view;

FIG. 9 is a front elevation view, thereof;

FIG. 10 is a rear elevation view, thereof;

FIG. 11 is a left side elevation, thereof;

FIG. 12 is a right side elevation view, thereof;

FIG. 13 is a top plan view, thereof;

FIG. 14 is a bottom plan view, thereof;

FIG. 15 is a top perspective view of the fluid dispensing stand and insert of FIG. 1, disassembled; and, FIG. 16 is a bottom perspective view, thereof.

The broken lines in the drawings depict portions of the fluid dispensing stand and insert that form no part of the claimed design.
